UNITED STATES PATENT OFFICE.

ADELARD PARENT, OF CHAPLEAU, ONTARIO, CANADA.

DYNAMO DRIVE FOR RAILWAY CARS.

Application filed September 8, 1925. Serial No. 55,100.

The present invention pertains to a novel drive for railway cars of the type comprising a dynamo shaft driven from an axle of the car.

5 The usual construction of this character includes pulleys on the axle and dynamo shaft and a belt trained over these pulleys. This device loses in efficiency due to the friction produced by the belt and is further 10 hindered in cold weather by the solidification of greasy substances accumulating on the belt.

The object of the present invention is to overcome these difficulties, and this object is 15 attained by use of toothed wheels on the axle and dynamo shaft with a drive chain trained over the wheels. The chain is so constructed that the teeth of the wheels engage in the links thereof, whereby motion is 20 positively transmitted from the axle to the dynamo shaft without slipping from the flexible connecting member.

A particular feature of the invention is 25 a novel accessory to the chain which diminishes friction between it and the toothed wheels particularly during shifting of the chain while the car travels around a turn. This construction embodies the use of U-shaped links which are interconnected to 30 form the chain, and loose roller sleeves surrounding the sides of the link. Consequen- tly, if the chain shifts in any direction relative to the toothed wheels, the resulting friction is decreased by the roller sleeves.

25 The invention is fully disclosed in the following description and in the accompanying drawings in which;

Figure 1 is a longitudinal section of a railway car, showing in elevation the device of 40 the invention;

Figure 2 is a plan view of the invention;

Figure 3 is a diametric section of the pulley on the dynamo shaft;

Figure 4 is a perspective view of one of 45 the split sections of the wheel on the axle; and

Figure 5 is a perspective view of a fragment of the drive chain.

Reference to these views will now be made 50 by use of like characters which are employed to designate corresponding parts throughout.

In Figure 1 are shown the concerned parts 55 of a railway car, namely, the floor 1, one of the axles 2, and a car wheel 3 mounted on the axle.

To the bottom of the floor 1 is secured an adjustable bearing comprising a track 4 and a hanger 5 slidable on the track. The hanger is adjustable with reference to the track by 60 means of screws 6 passed through ears 7 depending from the ends of the track. The hanger rotatably supports a shaft 8 which drives the dynamo (not shown) carried by 65 the car.

The dynamo shaft is caused to be driven from the axle by toothed wheels mounted on these parts and connected by a suitable flexible member. The wheel on the axle is a split member, each section including a semi-circular core 8' and an outer concentric channel 9. These parts are joined and held in fixed relation to one another by means of spokes 10 projecting from the outer surface of the core to the inner surface of the channel. The base of the channel, that is, the part between the flanges, is formed with a plurality of teeth 11 the purpose of which is pointed out below. The ends of each flange of the channel are provided with outwardly projected apertured ears 12 as clearly shown in Figure 4. In the assembly of a split wheel on the axle, the ears of one section coincide with the ears of the other section and are joined by bolts 13 passed 85 therethrough.

The wheel on the dynamo shaft is smaller than that already described as may be seen from Figure 1. This wheel consists of a core 14 of wood or other insulating material 90 formed with a tapered bore 15 into which the dynamo shaft is wedged. At one end of the bore is formed a socket 16 for the reception of a nut or the like to be secured on the shaft in order to prevent slipping of the core. The body 17 of this wheel surrounds the core and is formed with flanges 18 at the edges thereof. Between the flanges 18 is provided a series of teeth 19 similar to the members 11 already mentioned.

The two toothed wheels are connected by an endless chain consisting of a series of U-shaped links 20, the ends of each are hooked as at 21 around the bends 22 of the adjacent link. The chain is so constructed that when 105 it is trained around the toothed wheels the teeth 11 and 19 are received within the links so that the chain is moved by the rotation of the toothed wheel on the axle. This movement is transmitted to the wheel on the dynamo shaft and causes the latter to rotate.

The sides of the links are surrounded by

loose roller sleeves 23. These devices diminish the friction between the chain and the toothed wheels during the normal movement of the chain and also when the chain shifts with reference to the wheels while the car is passing around a bend.

While a specific embodiment of the invention has been illustrated and described, it is to be understood that various alterations in 10 the details of construction may be made without departing from the spirit of the invention as indicated by the appended claims.

Having thus fully described the invention, what I claim as new and desire to protect by Letters Patent is:

1. In combination with an axle and shaft, toothed wheels mounted on said axle and shaft, a chain consisting of interconnected U-shaped links trained over said toothed

wheels, the teeth of the wheels being received 20 in the links of the chain, and roller sleeves surrounding the sides of the links.

2. In combination with an axle and shaft, a split toothed wheel mounted on the axle, a toothed wheel mounted on the shaft, a chain 25 consisting of interconnected U-shaped links trained over said toothed wheels, the teeth of the wheels being received in the links of the chain, and roller sleeves surrounding the sides of said links.

3. A drive chain comprising a series of U-shaped links, hooks formed at the ends of each link and engaging the bends of the adjacent links, and roller sleeves loosely surrounding the sides of said links.

In witness whereof I have hereunto set my hand.

ADELARD PARENT.
